(74) *Attorney, Agent, or Firm* — Oyen Wiggs Green & Mutala LLP

(**) **Term:** **15 Years**

(57) **CLAIM**

The ornamental design for an accessory for portable electronic device, as shown and described.

DESCRIPTION

(21) **Appl. No.:** **29/706,881**

FIG. 1 is a rear view of an accessory for portable electronic device showing the design;

(22) **Filed:** **Sep. 24, 2019**

FIG. 2 is a right side view thereof;

(51) **LOC (13) Cl.** **14-02**

FIG. 3 is a front view thereof;

(52) **U.S. Cl.**

FIG. 4 is a top view thereof;

USPC **D14/440**

FIG. 5 is a first perspective view thereof;

(58) **Field of Classification Search**

FIG. 6 is a second perspective view thereof;

USPC D14/440; 206/45.23, 320, 45.2;
361/679.55; 294/25; 224/218

FIG. 7 is an exploded perspective view from the rear thereof;
FIG. 8 is an exploded perspective view from the front thereof;

CPC ... G06F 1/1628; G06F 1/1626; A47B 23/044;
H04B 1/3888; H05K 5/0217

FIG. 9 is a bottom view thereof, said view being at a larger
scale than the remaining views to more clearly show the
features visible therein;

See application file for complete search history.

FIG. 10 is a left side view thereof; and,

(56) **References Cited**

FIG. 11 is a cross-sectional view taken along line 11-11 in
FIG. 1.
